UNITED STATES PATENT OFFICE

WILLIAM C. AGERELL, OF CHICAGO, ILLINOIS

INTERNAL COMBUSTION ENGINE

Application filed April 13, 1928. Serial No. 269,671.

This invention relates to internal combustion engines and particularly to valve gears for such engines. It has for one object to provide a valve and a valve operating gear for internal combustion engines in which separate valves are used for intake and exhaust and in which the valves for the several cylinders are operated from a single valve operating mechanism. Another object is to provide an oscillating valve construction in which wear is reduced, large valve openings are provided and in which a simple and powerful unit mechanism for operating all the valves is also provided. Other objects will appear from time to time in the course of the specification and claims.

I illustrate my invention more or less diagrammatically in the accompanying drawings wherein:

20 Figure 1 represents a vertical cross section through the engine which is taken generally at line 1—1 of Figure 6;

Figure 2 is a detailed plan view of an exhaust valve seat showing the ports;

25 Figure 3 is a plan view of one of the valve discs;

30 Figure 4 is a detailed sectional view showing an inlet valve in position upon its valve seat; this view is taken looking upward along the cylinder and in effect is a sectional view taken on an enlarged scale on lines 4—4 of Figure 1;

35 Figure 5 is a sectional view showing the exhaust valve in the open position and is, in effect, a sectional view taken on line 5—5 of Figure 1, looking upward from the cylinder;

40 Figure 6 is a longitudinal vertical sectional view taken through the upper part of one-half of the cylinder head assembly of the engine, taken generally on line 6—6 of Figure 1;

45 Figure 7 is a plan view of Figure 6 with the cover removed showing the valve operating gear;

50 Figure 8 is a vertical longitudinal sectional detail taken on line 8—8 of Figure 7 showing the main or central valve operating mechanism;

55 Figure 9 is a detailed vertical cross sec-

tion with parts in elevation on an enlarged scale, taken approximately on the line 9—9 of Figure 6.

Like parts are designated by like characters throughout the specification and drawings.

In the form of my invention illustrated herewith A is a cylinder. The particular details of the cylinder construction form no essential part of the present invention and they will not be further described. As shown, the cylinder is of more or less conventional type and is water jacketed. A¹ is a piston mounted within the cylinder for reciprocation. A² is a crank shaft. A³ is one of the cranks formed on the shaft. A⁴ is a connecting rod mounted at one end on the crank A³ and at the other carries the piston A¹.

B indicates the combustion chamber formed in the cylinder head. B¹ is an inlet passage. It is provided with ports B² which communicate with the combustion chamber B and the cylinder generally. B³ is an inlet valve. It is provided with ports B⁴ which are adapted to register with the ports B² and it is mounted for rotation on a shaft B⁵. At its upper end the shaft carries a short crank arm B⁶ which is pivoted at its other end to the link B⁷. This link is pivoted to the arm B⁸, which arm is bent as shown, and is attached at its upper end to the slide rod B⁹. This rod carries a roller B¹⁰ mounted on a pin B¹¹, which roller is in contact with a cam which will be later described. At its upper end and beneath the crank B⁶ surrounding the shaft B⁵ is a spring B¹². B¹³ is a cover about the shaft B⁵ and covers the spring B¹².

90 The above description of the inlet valve applies with slight modifications to all of the valves. Each is operated from a cam which will be described below, and each is generally similar, the inlet and exhaust ports being identical in design and the valves differing only from each other in order to permit rods of different lengths to be attached and to connect the valve with the operating cam. The cam operating mechanism will 95 now be described.

C is a cam shaft. It is rotated from any suitable source. C¹, C² are bearing supports for the shaft. They are mounted in the head assembly in any suitable manner. As here shown they have feet C², C² which are mounted in the cylinder head casting. The slide rod B⁹ is mounted to slide in the members C¹, C¹. Other slide rods are C³, C⁴, C⁵, C⁶ and C⁷. Each of them carries a pin X similar to the pin B¹¹ and upon each pin is mounted for rotation a roller X¹. These rollers are in contact with the cam member C⁸. As the cam revolves with the revolution of the cam shaft C, the rollers follow its curvature, moving back and forth and carrying with them the slide rods upon which they are mounted. Each of these slide rods through a connecting member is adapted to oscillate a valve upon its shaft. Thus with each revolution or as the cam and cam shaft revolves, the valves are oscillated on their seats and so brought into and out of register with the ports to permit intake and exhaust. For each set of intake valves and exhaust valves, there is one operating cam. They may be substantially alike in design and proportion. They will normally be varied merely to provide a symmetrical design on the engine, and of course the curvature on the intake and exhaust cam may be varied.

D is an exhaust passage. It is provided with ports D¹. D² is an exhaust valve provided with ports D³ and mounted upon a shaft or stem D⁴. As shown in Figure 5, the exhaust valve is in position and the valve ports D³ are in register with the exhaust ports D¹ and the valve is thus opened and an exhaust takes place. At its upper end the valve shaft D⁴ carries a crank D⁵ which is pivoted at its other end to the link D⁶. This link is pivoted to the arm D⁷ which itself is fastened to a slide rod D⁸. This rod is mounted for operating movement in the supporting member D⁹ which also carries a cam shaft E similar to the cam shaft C above mentioned. The members D⁹ are provided with feet D¹⁰ by means of which they may be mounted upon and secured to any suitable portion of a head assembly casting. The slide rod D⁸ carries a roller D¹¹ which is mounted for rotation upon a pin D¹².

This roller is in contact with a cam E¹ which is pivoted upon and adapted to rotate with the cam shaft E. As the cam rotates, the slide rod is moved backwards and forward with the result that the valve rod D⁴ is oscillated and the valve itself oscillated. Other slide rods F, F¹, F², F³ and F⁴ are similarly mounted in the members D⁹ for sliding movement. Each carries a roller Y similar to the roller D¹¹ and mounted upon a pin Y¹ similar to the pin D¹². Projecting downwardly from the sliding rod F is an arm F⁵ which is connected to a reach rod F⁶. This rod has pivoted at its outer end a

crank F⁷ which is attached to the valve stem or shaft F⁸ and a valve F⁹.

The other valves are similarly connected to separate slide rods, with the result that each rod is attached to a single slide rod and moved by it. The details of this construction will not be repeated, as they are similar throughout except for the fact that they vary somewhat due to the difference in distance of the valves from the valve operating cam. Each of the valve rods has about its upper end a spring B¹² or G which tends to hold it upon its seat. The valves adjacent the cam operating mechanism have covers B¹³ or G¹ about the springs which prevent the leakage of too much lubricant from the cam operating mechanism along the valve stem to the valve.

H, H indicate cooling passages located between the discharge and inlet ports. It will be seen that each inlet and each discharge port is thus surrounded on three sides by water passages and thus the cylinder head and the ports in particular are effectively cooled.

The use and operation of this invention are as follows:

In a general way the engine itself operates in the usual manner of an internal combustion engine. A charge is drawn in to the combustion chamber through the inlet passage or through the inlet valve which is opened at the proper time in the engine cycle to permit the entrance of the charge. The charge is compressed. It is ignited by a spark plug or any other suitable means. The charge is burned and the piston is forced down. At the appropriate time the exhaust valve is opened and the discharge with the burned gases takes place. The cycle of the engine is repeated in this fashion so long as the engine operates. In the particular form of the invention shown herewith there are six engine cylinders and six inlet and six exhaust valves. The inlet valves are operated by a single mechanism embodying one cam shaft and cam assembly, slide rods and connecting rods to the several valve shafts so that the valves are oscillated and thus moved to open and close at appropriate times. A similar arrangement is provided for the exhaust valves, there being another cam shaft and cam assembly, slide rods and connecting rods, each connected to one of the valve shafts so that this set of valves is operated for opening and closing. The two cam shafts may be operated from the engine in any suitable manner. The details of the timing can be considerably varied. In the form of the engine shown herewith the parts are so proportioned and assembled that the details of operation are generally as follows:

The cam shaft mechanisms are driven from the motor shaft so that the cam shafts preferably make one revolution to two revolutions

of the crank shaft. Let us suppose now that the piston is to move upward on the exhaust stroke. The parts are thus arranged in Figure 1. The cam roller governing the exhaust valve is shown in Figure 1 and is in engagement with the cam slot. The sliding rod is reciprocated and through the link and crank it oscillates the exhaust valve shaft and through it the exhaust valve to open the exhaust ports. As shown in Figure 1 the exhaust valve disc is so positioned that its ports are in full register with the ports of the valve seat. After the ports have remained in full register for approximately 40° of piston travel, the valve commences to close rapidly and is completely closed when it has moved through about one-eighth of a revolution. With the parts designed as shown, this closing is complete about 8° after the piston has reached its upper dead center. By this arrangement the scavenging effect is increased and is aided by the free discharge of the exhaust gas.

The inlet valve starts to move at about 19° before the piston has reached its upper center and the inlet ports commence to come into register at about 12° after the piston has reached its upper center. The inlet valve thus has a lead of about 31°. The inlet valve commences to move slowly but at the instant that the ports begin to register the speed of motion of the valve is very rapid. One-eighth of a revolution of the valve disc would bring the ports of the disc in full register with the ports of the inlet opening. The valve rests in this position for 20° of piston travel and then closes rapidly.

After the piston has reached its lower limit of movement the compression stroke takes place without any further movement of the valve discs and there is no movement of the valve discs during the burning of the fuel. Just before the end of the firing stroke is reached when the pressure of the cylinder is near a minimum, the exhaust ports start to open rapidly and become fully opened after one-eighth of a revolution. The cycle above described for one cylinder is carried out in all cylinders. It will be understood, of course, that the timing and particular arrangements are not essential and might be infinitely varied. The details are inserted here, however, to describe the particular cycle of the form of the device shown herein.

The cam slot and associated parts are so designed that the valve action is positive at all times and motion of the valve discs takes place only a times when the pressures are at or near a minimum. Only one positive inlet cam and one positive outlet cam are necessary to actuate the valve operating mechanism for the six cylinders. Each set of valves is thus operated from a central point. It may be desirable to have two units control the intake

and exhaust on a twelve or sixteen cylinder engine. The valve discs are constantly resting upon a water cooled valve seat. They are thus cooled and enabled to stand high temperatures and the heat is thus dissipated by direct conduction at all times.

I claim:

1. In combination in an internal combustion engine having a plurality of cylinders, a plurality of exhaust valves and of inlet valves, a single cam assembly for individually controlling the valves of each set and separate connecting members extending from cam means to the several valves of each set, respectively, whereby the exhaust valves are individually operated from a single cam assembly and the inlet valves are individually operated from a single cam assembly.

2. In combination in an internal combustion engine having a plurality of cylinders, a plurality of exhaust valves and of inlet valves, a single cam assembly for each set of valves and connecting members from said cam means to each of said valves, said connecting members being grouped about the respective cam means for selective operation thereby, whereby the exhaust valves are selectively operated from a single cam assembly and the inlet valves are selectively operated from a single cam assembly, said valves being of the disc type mounted for oscillation, said cam assembly adapted to selectively oscillate them.

3. In combination in an internal combustion engine having a plurality of cylinders, a plurality of exhaust valves and of inlet valves, a single cam assembly for each set of valves and connecting members from said cam means to each of said valves, said connecting members being grouped about the respective cam means for individual intermittent operation whereby the exhaust valves are individually and intermittently operated from a single cam assembly and the inlet valves are individually and intermittently operated from a single cam assembly, including ported disc members located within the combustion chamber, shafts upon which the valves are mounted, the shafts being oscillated individually and intermittently by means of the respective cam assembly.

4. In combination in an internal combustion engine, a plurality of combustion chambers, inlet and exhaust openings for each, a valve mounted to control each of such openings and a unitary means for selectively oscillating individual valves of selected groups of said valves to open and close said openings.

5. In combination in an internal combustion engine, a plurality of combustion chambers, inlet and exhaust openings for each, valve discs mounted to control each of such openings and a unitary means for selectively oscillating individual disks of selected

groups of said discs to open and close said openings.

6. In combination in an internal combustion engine, a plurality of cylinders, inlet and exhaust disc valves for each of said cylinders and a single means for operating a plurality of said valves, including a cam, means for rotating such cam, reciprocatory members positioned to be individually reciprocated by the rotation of said cam, and links connecting said reciprocatory members with the valves whereby the reciprocation of said members transmits an oscillating motion to the valves.

15 7. In combination in an internal combustion engine, a plurality of cylinders, inlet and exhaust disc valves for each of said cylinders, said valves being mounted on shafts, and a single means for operating a plurality of said valves, including a cam, reciprocatory members positioned to be individually and selectively reciprocated by the rotation of said cam, and links connecting said reciprocatory members to said shafts 20 whereby the reciprocation of said members transmits an oscillating motion to said shaft.

25 8. In combination in an internal combustion engine, a plurality of cylinders, inlet and exhaust disc valves for each of said cylinders and a unitary means for operating a plurality of said valves, including a single cam for inlet and exhaust valves, respectively, reciprocatory members adapted to be reciprocated by the rotation of said 30 respective cams, arms and bosses on said reciprocatory members of such shape and located at the correct timing angle, so as to transmit the true reciprocating motion that the rotation of the cam offers, and links 35 connecting said reciprocatory members to said valves whereby the reciprocation of said members transmits an oscillating motion to the valves.

40 9. In combination in an internal combustion engine, a plurality of cylinders, inlet and exhaust disc valves for each of said cylinders, said valves controlling inlet and exhaust openings in each of said cylinders, and a single means for operating a plurality of said 45 valves, including a cam, reciprocatory members adapted to be reciprocated by the rotation of said cam, arms and bosses on said reciprocatory members of such shape and location as to transmit the true reciprocating 50 motion that the rotation of the cam offers, links connecting said reciprocatory members whereby the reciprocation of said members transmits an oscillating motion to the said 55 inlet and exhaust disc valves.

60 10. In combination in an internal combustion engine, a plurality of combustion chambers, inlet and exhaust ports for each chamber, a valve mounted to control each of said ports, unitary means for controlling selected 65 groups of said valves and including single

cam means for the inlet and exhaust valves respectively, and individual connecting members between the several inlet and exhaust valves and their respective cam means, said connecting members being grouped about their respective cam members and disposed in correct timing angle with respect thereto.

70 11. In combination in an internal combustion engine, a plurality of combustion chambers, inlet and exhaust ports for each chamber, a valve mounted to control each port, unitary means for operating selected groups of the valves and including single cam means for the inlet and exhaust valves respectively, means for rotating the cams, and individual connecting members between the several inlet and exhaust valves and their respective cams, said connecting members being positioned concentrically about the axes of rotation of the respective cams and being angularly spaced in correct timing angle for operation in a predetermined sequence.

75 12. In an internal combustion engine, a cylinder provided with inlet and exhaust passages, hollow members extending transversely of said passages and defining ports for the cylinder, disk valves controlling said ports and mounted in heat transfer relation to said transverse members, and means for circulating a cooling fluid through said hollow members.

80 13. In combination, a plurality of chambers each provided with inlet and outlet ports, a valve mounted to control each of said ports, and a unitary means for positively operating individual valves of selected groups of valves to open and close said ports.

85 14. In combination, a plurality of chambers each provided with inlet and outlet ports, inlet and exhaust disk valves for controlling the flow of fluid to and from each of said chambers, and a single means for operating a plurality of said valves including a cam, means for rotating said cam, reciprocatory members positioned to be individually reciprocated by rotation of the cam, and members connecting said reciprocatory members with the valves whereby the reciprocation of said members transmits an oscillatory motion to the disk valves.

90 Signed at Chicago county of Cook and State of Illinois, this 6th day of April, 1928.
